UNITED STATES PATENT OFFICE.

ROBERT A. KINKELE, OF STAPLETON, NEW YORK.

FIREPROOF FLOOR.

SPECIFICATION forming part of Letters Patent No. 592,117, dated October 19, 1897.

Application filed February 27, 1897. Serial No. 625,262. (No model.)

To all whom it may concern:

Be it known that I, ROBERT A. KINKELE, a citizen of the United States, residing at Stapleton, in the county of Richmond and State of New York, have invented certain new and useful Improvements in Fireproof Floors, of which the following is a specification.

The present invention relates to an improved construction of fireproof floor, being especially an improvement over the invention of R. A. Kinkele and Charles L. Wolff, covered by Patent No. 566,189, dated August 18, 1896. The invention is designed with a view to greater strength to withstand compressive strains and to provide for safety in case of overloading. In said patent the supporting-blocks—that is to say, ceiling-blocks—rested themselves directly on the bottom flanges of the beam and received the weight of the floor or filling blocks mostly upon their ends, while in the present invention the ceiling-blocks, strictly speaking, do not act as supports for the ordinary weight imposed on the floor-blocks, inasmuch as the main support is provided by separate skewbacks or blocks, which are constructed to fit against and interlock with the bottom flanges of the beams, said ceiling-blocks being supported upon the inclined faces of the skewbacks, so that when a crushing weight is imposed upon the floor-blocks the extra weight will be taken up by the ceiling-blocks and transmitted by end thrust to the skewbacks, thereby preventing the falling of the floor. The floor-blocks are made in three sections—namely, two end sections and a central or key section—while the upper and opposite side portions of the adjacent blocks, so constructed, are flattened and widened so as to abut and form a substantial floor-support.

In the accompanying drawings, Figure 1 is a perspective view of my improved fireproof floor. Fig. 2 is a side elevation with the supporting-beams in section. Fig. 3 is a broken side elevation of a floor-block. Fig. 4 is an end elevation of a floor-block and two skewbacks, showing their relative positions in the floor. Fig. 5 is a transverse section on line 5—5, Fig. 2.

Similar letters of reference indicate corresponding parts.

A A represent the I-beams or angle-irons,

on the flanges *a* of which the parts composing my improved fireproof-floor construction are supported.

The floor consists of a series of similar skewbacks B, ceiling-blocks C, and a series of filling or floor blocks D, alternating with the skewbacks and ceiling-blocks, and being each composed of two end sections *d* and intermediate key-section *d'*.

The skewbacks or blocks, ceiling-blocks, and floor-blocks are all of approximately the same contour in cross-section—namely, polygonal—so that the skewbacks or blocks each have a flat bottom *b*, parallel widened and flattened sides *b' b'*, extending at right angles to the bottom *b*, and at the upper part converging or inclined sides *b² b²*, while the ceiling-blocks have a flat bottom *C'*, flattened sides *C² C²*, and converging or inclined upper sides *C³ C³*, of which *C' C'* correspond with *b b*, *C² C²* with *b' b'*, and *C³ C³* with *b² b²*, respectively, of the skewbacks. The floor-blocks D have flat tops *d²*, parallel widened and flattened sides *d³ d³*, and converging or inclined under sides *d⁴ d⁴*.

The skewbacks or blocks are provided at their lower or base portions with transverse end recesses *b⁰*, which receive the lower flange *a* of the I-beams A and support the skewbacks and the ceiling-blocks C, which are arranged between them. The adjacent or abutting ends or faces of the skewbacks or blocks and the ceiling-blocks are inclined or slanting, so that the ceiling-blocks will be supported against the skewbacks, while the weight of the ceiling-blocks will force the skewbacks and ceiling-blocks outwardly against the beams. Lateral thrust is prevented by arranging the parallel lower sides of the skewbacks and ceiling-blocks in one line in contact with those on the next line.

The angular spaces between the inclined surfaces of the skewbacks and ceiling-blocks receive the floor or filling blocks D, which are arched underneath so as to impart greater strength, and which rest at their outer ends upon the inclined surfaces *b²* of the skewbacks B. The end sections of the floor-blocks are forced in contact with the webs of the beams A by means of the interposed keys *d'*, so that each floor-block is self-sustaining, its ordinary points of support being upon the

skewbacks. The effect of this is that a fire-proof floor is produced which is independent of the ceiling-blocks, and these are, however, of great importance when an extraordinary weight sufficient to crush each single arch floor-block is imposed on the latter, as then the center of the floor-block rests upon the ceiling-blocks, whereby the structure is prevented from falling. The extra weight im-

10 parted to the ceiling-blocks really tends to make the structure less dangerous than otherwise, as the skewbacks are thereby more firmly thrust against the supporting-beams.

15 The joints are cemented up in a suitable manner, and the floor-blocks can be made hollow in the form shown or in any other suitable manner.

Having thus described my invention, I claim as new and desire to secure by Letters

20 Patent—

1. A fireproof floor, consisting of a series of skewbacks or blocks, a series of ceiling-blocks supported by and between the same, and a series of floor-blocks, arranged to alter-

25 nate with the skewbacks and ceiling-blocks, and being normally supported from the ends, by the skewbacks, whereby the normal load is transferred directly to the skewbacks, substantially as set forth.

30 2. A fireproof floor, consisting of flanged supporting-beams, recessed skewbacks or

blocks, the recesses of which receive the flanges of the beams, a series of ceiling-blocks supported by and between the skewbacks, and a series of floor-blocks, arranged to alternate with the skewbacks and ceiling-blocks, and being normally supported from the ends, by the skewbacks, substantially as set forth. 35

3. A fireproof floor, consisting of a series of skewbacks or blocks, a series of ceiling-blocks supported by and between the same, and a series of floor-blocks, arranged to alternate with the skewbacks and ceiling-blocks, said floor-blocks having approximately parallel sides at their upper parts and converging under sides, substantially as set forth. 40

4. A fireproof floor, consisting of a series of skewbacks or blocks, and a series of floor-blocks arranged to alternate with the skewbacks, and the meeting surfaces of the skewbacks and floor-blocks converging, so that the floor-blocks are normally supported from the ends, by the skewbacks, whereby the normal load is transferred directly to the skewbacks, substantially as set forth. 45

50 In testimony that I claim the foregoing as my invention I have signed my name in presence of two subscribing witnesses.

ROBERT A. KINKELE.
